UNITED STATES PATENT OFFICE.

JAMES McMILLEN, OF ALLEGHENY, PENNSYLVANIA.

FRUIT-JAR.

SPECIFICATION forming part of Letters Patent No. 341,341, dated May 4, 1886.

Application filed September 9, 1885. Serial No. 176,576. (No model.)

To all whom it may concern:

Be it known that I, JAMES McMILLEN, a citizen of the United States, residing at Allegheny, in the county of Allegheny and State 5 of Pennsylvania, have invented certain new and useful Improvements in Fruit Jars and Cans, of which the following is a specification, reference being had to the accompanying drawings.

10 My invention relates to an improvement in fruit jars and cans; and it consists in the combination of the jar, provided with a flange, on which are formed inclines, and grooved neck, with a rubber packing which is placed 15 in the groove, the cover, and a bent wire for securing the cover in position, as will be more fully described hereinafter.

To hermetically close fruit jars or cans, many devices have been adopted that differ 20 essentially from my invention; but some approach it more or less, and among them are those that surround the neck of the jar by a band over which the cover is placed. The neck of the latter kind is made conical to increase the resistance when the top is pressed 25 down and the band is confined in a recess, leaving a space between the band and the body of the jar unoccupied, while the flange of the cover rests on a shoulder around the 30 neck. The conical form of the neck has a tendency to let the cover slip off, and the close contact of the cover with the shoulder upon which it rests makes the removal of the cover difficult. To avoid these objections is the object of the present invention, which is hereinafter described.

The accompanying drawings represent my invention.

Figure 1 shows the cover in its place on the 40 jar. Fig. 2 represents the cover detached. Fig. 3 is a vertical section of the upper portion of a jar.

A represents the cover of the jar. Its top a is level or flat, and its rim or flange b at a 45 right angle with the top. The width of the flange does not exceed half an inch, and has on its edge a rounding bead, c, to add strength and prevent expansion.

The material employed for the cover may 50 be sheet metal or glass of sufficient thickness to resist the force required to press it firmly

down over the neck of the jar. The rectangular form is given to make the flange b gain a firm hold and adhere to its place, which, if conical, it is liable to lose by sliding upward 55 when pressed against from underneath at the inside.

The length of the neck B of the jar exceeds the width of the flange b, so that when the cover is placed upon it and pressed down its 60 top rests on the neck, while the bead c on the flange does not touch the body of the jar, but remains free.

Surrounding the upper end of the neck is a narrow band or projection, d, that, when the 65 cover is placed over it, fits in the flange b. Below the projection d the neck continues vertically downward to the body J of the jar, and terminates at a flange, f, surrounding the upper portion of the jar. On the part of the 70 neck between the projection d and the flange f a rubber band, h, is placed, that not only wholly occupies that space, but its thickness slightly protrudes from it, so that when the cover is pressed down the band is thereby compressed, forming a reliable hold to the vertical 75 sides of the cover.

The flange f around the jar is of uniform thickness, excepting at two places diametrically opposite one another, where it gradually increases, and again diminishes in thickness, forming four inclines, g, (two pairs on each side of the neck,) for the purpose of increasing the pressure of a removable wire, h', passing over the cover, having both its ends 80 bent to clasp the flange. This wire h' is passed over the cover from the sides, and its ends are made to catch under the two inclines g.

Having thus described my invention, I claim—

In a fruit-jar, the combination of the jar J, provided with the flange f, on which are formed the inclines g, and the grooved neck d, with the rubber packing h, the cover A, and the wire h', substantially as shown and described.

In testimony whereof I affix my signature in presence of two witnesses.

JAMES McMILLEN.
